US00D982166S

(12) **United States Design Patent** (10) **Patent No.:** **US D982,166 S**
(45) **Date of Patent:** **** Mar. 28, 2023**

(54) **INCONTINENCE TREATMENT DEVICE**

(71) Applicant: **Furun Healthcare Co., Ltd.**, Wonju-si (KR)

(72) Inventor: **Byoungmo Kang**, Wonju-si (KR)

(***) Term: **15 Years**

(21) Appl. No.: **35/512,525**

(22) Filed: **Mar. 9, 2021**

(80) **Hague Agreement Data**

Int. Filing Date: **Mar. 9, 2021**

Int. Reg. No.: **DM/215503**

Int. Reg. Date: **Mar. 9, 2021**

Int. Reg. Pub. Date: **Sep. 10, 2021**

(30) **Foreign Application Priority Data**

Mar. 5, 2021 (KR) 30-2021-0010884

(51) **LOC (14) Cl.** **24-01**

Assistant Examiner — Holly M Rodriguez

(57) **CLAIM**

The ornamental design for an incontinence treatment device, as shown and described.

DESCRIPTION

1. Incontinence treatment device

1.1 : Perspective

1.2 : Front

1.3 : Back

1.4 : Left

1.5 : Right

1.6 : Top

1.7 : Bottom

(Continued)

It is to be seated by an user so that the perineal region of the user should be positioned on the electric stimulation part formed on the center of the device.

1 Claim, 3 Drawing Sheets
